US0D1015653S

(12) **United States Design Patent** (10) **Patent No.:** **US D1,015,653 S**
(45) **Date of Patent:** **** Feb. 20, 2024**

(54) **ULTRAVIOLET DISINFECTION APPARATUS**

(71) Applicant: **AEOLUS ROBOTICS SINGAPORE PTE. LTD.**, Singapore (SG)

(72) Inventor: **Reinier Bloem**, Taipei (TW)

(73) Assignee: **AEOLUS ROBOTICS SINGAPORE PTE. LTD.**, Singapore (SG)

(**) Term: **15 Years**

(21) Appl. No.: **29/815,803**

(22) Filed: **Nov. 16, 2021**

(51) **LOC (14) Cl.** **24-02**

(52) **U.S. Cl.**

USPC **D24/217; D24/210; D26/72; D26/118; D32/1**

(58) **Field of Classification Search**

USPC **D32/1; D23/355, 364; D24/210, 217; D26/72, 74, 76, 93, 118; D15/199**

(57) **CLAIM**

The ornamental design for an ultraviolet disinfecting apparatus, as shown and described.

DESCRIPTION

FIG. 1 is a top, front, right side perspective view of an ultraviolet disinfecting apparatus, showing my new design; FIG. 2 is a top, rear, right side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is a top, rear, right side perspective view thereof, showing the ultraviolet disinfecting apparatus in a disassembled configuration. The broken lines depict battery and portions of the ultraviolet disinfecting apparatus that form no part of the claimed design.

1 Claim, 9 Drawing Sheets
